BAG CLOSURE

Filed June 20, 1927

UNITED STATES PATENT OFFICE

JAMES K. DIAMOND, OF GRAND RAPIDS, MICHIGAN

BAG CLOSURE

Application filed June 20, 1927. Serial No. 199,975.

The main object of this invention is to provide an improved bag closure which is effective in closing bags containing heavy materials such as cement, lime and the like, and also one which is capable of rapid manipulation thereby adapting it for bags requiring rapid opening and closing such as mail bags and bags repeatedly used for transporting various materials.

10 A further object is to provide a closure having these advantages which may be effectively locked or sealed.

Objects pertaining to details and economies of my invention will appear from the description to follow. The invention is pointed out in the claims.

A structure embodying the features of my invention is clearly illustrated in the accompanying drawing, in which:

20 Fig. 1 is a perspective view of a bag embodying the features of my invention with the bag closed.

Fig. 2 is a fragmentary perspective view of a bag embodying the features of my invention with the closure open.

Fig. 3 is an enlarged detail showing the means for supporting the closure upon the bag and the relation of the parts.

Fig. 4 is a detail section on a line corresponding to line 4—4 of Figs. 1 and 3.

Fig. 5 is a fragmentary edge view showing the closure secured by means of a seal of the car seal type.

Fig. 6 is a fragmentary perspective view illustrating the manner of adjusting the bag to a filling spout.

Referring to the drawing, 1 represents a fabric bag open at one end, the opening being provided with beaded edges 2 formed by 40 turning the edges over the cords 3 and the inturned flap portions 4 being disposed on the inner sides of the walls of the bag. These inturned portions are secured by rows of stitching 5 adjacent the beads and adjacent 45 the edge of the flap.

The tubular closure member 6 has a longitudinal slot 7 of such width as to receive the walls of the bag between them, the diameter of the closure being such as to receive the 50 beaded edges 2 of the bag as shown in Figs.

3 and 4. The combined width of these beaded edges substantially exceeds the width of the slot so that it is impossible for the beads to pass through the slot when the closure is slipped over the beads with the beads lying side by side.

The closure is slidably supported by the tubular support 8 which has ears 9 lapping upon the sides of the bag and secured by rivets 10 arranged through the side walls as shown in Fig. 4. The flaps 4 are of such width that the rivets pass therethrough, thereby providing a very secure attachment for the support to the bag.

The closure member is preferably provided with annular beads 11 providing stops adjacent its ends which coact with the support to limit the opening and closing movement of the closure member and retain it in assembled relation to the support.

The closure member is of such length that when closed, its ends project beyond the edge of the bag, its projecting end having a hole 12 therethrough to receive a locking or retaining means such as the seal 13.

When the closure member is in bag closing position it constitutes an effective grip or hand hold by which the bag may be handled.

The bags may be rapidly opened and closed and may be opened to any extent desired, thus particularly adapting them for attachment to a filling spout, the bag being slipped upon the spout, as 14, and the closure adjusted to clamp or close the bag upon the spout. The closure is manipulated as the bag is withdrawn from the spout so that it is completely closed substantially as soon as it slips from the spout, which is also a feature of advantage.

Bags embodying my improved closure are adapted for use in various relations as for cement, lime and the like, or where the bag is to contain heavy materials. The structure is also desirable for use in bags where it is necessary to quickly open and close the bags as in mail bags and the like.

I have, however, only illustrated my improvements as adapted to a plain type of bag as it is believed this disclosure will enable

those skilled in the art to embody or adapt my improvements as may be desired.

Having thus described my invention, what I claim as new and desire to secure by Letters Patent, is:

- 5 1. In a bag closure, the combination of a bag provided with beaded edges, a tubular closure member telescopingly associated with said beaded edges and slotted to receive the walls of the bag adjacent its said beaded edges, a tubular support secured to said bag at one end of its opening, said closure being slideable in said support and provided with stops adjacent its ends coacting with said support, 10 the other end of said closure projecting beyond the bag and being perforated to receive a lock or seal.
- 15 2. In a bag closure, the combination of a bag provided with beaded edges, a tubular closure member telescopingly associated with said beaded edges and slotted to receive the walls of the bag adjacent its beaded edges, and a tubular support secured to said bag at one end of its opening, said closure being slideable in said support.
- 20 3. In a bag closure, the combination of a bag having an opening provided with beaded edges, a longitudinally slotted tubular closure telescopingly engaging the said beaded edges, a supporting sleeve for said closure member secured to said bag, said closure member being provided with stops coacting with said sleeve, and means for retaining said closure member in bag closing position.
- 25 4. In a bag closure, the combination of a bag having an opening provided with beaded edges, a longitudinally slotted tubular closure telescopingly engaging the said beaded edges, and a supporting sleeve for said closure member secured to said bag, said closure member being provided with a stop coacting with said sleeve.
- 30 5. In a bag closure, the combination of a bag having an opening provided with beaded edges, a longitudinally slotted tubular closure telescopingly engaging the said beaded edges, and a supporting sleeve for said closure member secured to said bag.
- 35 6. In a structure of the class described, the combination with a bag provided with thickened top edges, a tubular closure member longitudinally slotted to receive the walls of the bag and telescopingly embrace the said thickened edges thereof, and a tubular support for said closure member provided with attaching ears lapped upon the opposed walls of the bag and secured thereto to slidably support the closure member in position to telescopingly embrace the said top edges of 40 said bag.
- 45 7. In a structure of the class described, the combination with a bag provided with thickened top edges, a tubular closure member longitudinally slotted to receive the walls of the bag and telescopingly embrace the said

thickened edges thereof, and a support member secured to said bag to slidably support the closure member in position to telescopingly embrace the said top edges of said bag.

In witness whereof I have hereunto set 70 my hand.

JAMES K. DIAMOND.
